Ralph A. Zelli
INVENTOR.

UNITED STATES PATENT OFFICE

RALPH A. YELLI, OF LOS ANGELES, CALIFORNIA, ASSIGNOR OF ONE-FIFTH TO
H. MISCHLER, OF LOS ANGELES, CALIFORNIA

AIRSHIP CONSTRUCTION

Application filed November 11, 1929. Serial No. 406,310.

This invention relates to improvements in airships or to lighter than air craft and more particularly to improvements directed to obtaining better stabilization and equilibrium.

A further object of this invention is to provide a simple, efficient and inexpensive device of this kind wherein the features of convenient accurate control of the equalizing parts is given to the ship's pilot and navigator.

Another object of this invention is to provide reinforcing means and parts for the envelope of the airship with a novel disposition and arrangement of girders and beams all designed to make the airship as light and strong as possible.

A still further object thereof is to provide a new type of airship with a series of radially disposed air shafts opening out thru the nose end thereof to which compressed air is conducted in a selective manner that will assure compressed air passing thru one or more of the predetermined air shafts; a main air tunnel being provided which is connected with the separate air shafts and being also connected with a blower or suction fan, from which leads an intake pipe out of the lower section of the envelope with a terminal arranged exteriorly of the airship and pointing in the direction of the rear of the airship.

A further object of this invention is to provide at the front end of the airship a stabilizing and steering mechanism of a form disclosed in a copending application filed January 29th, 1929, bearing Serial Number 335,844, which includes a series of forwardly projecting air shafts, propellers mounted externally of the airship and carried by said shafts, and a tunnel delivering compressed air thru said air shafts selectively.

Another object of this invention is to so construct the envelope thereof as to provide a coextensive series of dead air spaces whereby to insulate the temperature and atmosphere so that it may not unduly affect the internal surfaces of the airship.

A still further object of this invention is to provide shutters or dampers in the several air shafts with selective controlling means

within ready reach of the pilot, navigator or operator of the machine for the purpose of making it possible for the operator to open any one or more of the air shafts independently of one another for the reception of compressed air.

With the above and other objects in view my invention consists in the combination, arrangement and details of construction disclosed in the drawings and specification, and then more particularly pointed out in the appended claims.

In the drawings, wherein similar reference characters designate similar parts throughout the respective views,

Figure 1 is a side elevation, partly in section, showing one form of my invention,

Figure 2 is a front end elevation of my invention,

Figure 3 is a cross sectional elevation taken on line 3—3 of Figure 1,

Figure 4 is a fragmental detail view showing the controls for the shutters of the air shafts forming part of my invention,

Figure 5 is a side elevation of my invention, partly broken away to disclose a modification of the air shafts,

Figure 6 is a cross sectional elevation on line 6—6 of Figure 5,

Figure 7 is a detail fragmental view of the bracing members for the airship envelope, and

Figure 8 is a cross sectional elevation taken on line 8—8 of Fig. 5.

Referring to the drawings which are merely illustrative of my invention the various parts of my invention are disclosed. The envelope of appropriate design and construction is designated 10 and it has its front nose end formed rotund as at 12 and its rear end tapering as at 11 at which section the vertical rudders 13 and the horizontal rudders 14 are provided. The main length of the envelope 10 of the airship will be of preferably double-wall construction the thin walls being designated 10a, 10b leaving a coextensive space therebetween as at 15 in which dead air spaces 16 will operatively be formed. The dead air spaces extending all around the exterior surfaces of the envelope

10 will assure insulation inside of the envelope of the atmospheric temperature as well as atmospheric disturbances, so that the temperature within the envelope will be constant.

5 It is desired to reinforce the envelope in a manner to make it light and strong and for this purpose there is provided suitable bracing means designed to provide a durable structure.

10 It will be seen that the interior of the envelope 10 will be provided with a plurality of adjacent inflatable bulkheads M at spaced about points. The double-walled exterior 15 surface of the envelope will be reinforced by means of the diagonal and rectilinear braces or struts 17 and 18 arranged in separate units in a manner to cause the diagonal struts 17 to converge at their upper and lower ends 20 where they are connected to the adjacent parts of the envelope 10. The rectilinear struts 18 connect lateral points of the airship envelope. A central tubular reinforcement may be employed designated 22 in Figure 7 25 and built thereinto internally are the circular series of struts 23 clustered in snug formation and securely anchored to radially extending rods or stanchions 24 also connected to the envelope at their ends.

30 In a co-pending application there has been described an arrangement of parts for producing stabilization of the airship wherein use is made of a longitudinal central air tunnel 21 connected at its inner end to a 35 source of air compression such as the casing F in which an air compressor engine is located, from which casing leads the conduit A in the interior of which B air is sucked thru in a manner explained in a former application. From a motor C-connections lead 40 into the interior of this casing F. The air tunnel 21 connects at its forward end with a series of radially disposed forwardly diverging air shafts each communicating with 45 the air tunnel. The air shafts and the concentric air tunnel all open out of the nose end of the envelope 10 of the airship to the atmosphere, and propellers 31 may be mounted upon the air shafts designated respectively 27, 28, 50 29 and 30 the inner ends of which air shafts being contracted as at 27a, 28a, 29a and 30a respectively, the interior of the air tunnel being designated 21a. This arrangement of parts produces at the front section of the machine a stabilizing apparatus consisting of the 55 series of radially disposed air shafts, two of which are arranged at the dead centers of the machine and the other two being arranged at right angles thereto preferably as shown in 60 Figure 4. As has been explained in a co-pending application the purpose of these air shafts is to assist in steering and stabilizing the airship when in flight in order to maintain at all times an even keel and particularly thru the selective actuation of the

dampers or shutters of the air shafts, to prevent listing of the airship.

Mechanism is provided for controlling predeterminedly and selectively the dampers, shutters or valves located in the several air shafts. 33 designates the usual circular damper one of which is disposed in each air shaft, being mounted upon the pintle 35 passing thru the particular air shaft and connected externally of the air shaft to an actuating crank 32' to which is connected the connecting rod or pitman 32 which at its lower end is connected to another crank 36' fixed upon a common shaft 37 suitably mounted in bearings. There is a separate operator's handle 36 associated with each separate connecting rod 32 connected to one of the four cranks 32' controlling opening and closing of the dampers or shutters. These handles or levers 36 have latches and racks (not shown) usually associated with such devices for operating the connecting rods. Hence by the operator taking hold of the right lever 36 and moving the same over the proper arc one connecting rod 32 will be caused to open or close one damper or shutter 33 of one air shaft. Hence the operator may selectively operate so as to open or close one or more of the shutters. It will be understood that each lever 36 will operate the crank 36', the latter disposed loosely upon the shaft 37 if desired so that all of the connecting rods will not be operated at the same time.

It will also be observed that the control or operator's room is located at the extreme front or nose end of the airship envelope 10 as shown in Figure 1. The controls consisting of the hand levers and the cranks are located on the floor of the operator's cabin so that the pilot or navigator may be seated and may operate the controls readily. In order to give the operator a commanding view of the flying conditions ahead of him and to enable him to determine when to operate what shutters to maintain proper stabilization of the airship there is provided in front of the operator in the nose end of the envelope 10 a sight opening 20a covered with window glass. Another such glass sight opening may be provided as at 20 at the upper part of the front nose surface of the airship. By thus arranging the windows at the nose end of the airship it is possible to see to better advantage how the ship behaves and this makes it possible to control the air shafts more conveniently.

My invention of stabilizing apparatus, located at the front section of the airship, is designed equally well for use on dirigibles of conventional design and construction as on the particular type of airship disclosed in the co-pending application and also disclosed in Figure 1. For this purpose the arrangement is made use of which is disclosed in Figure 5. Here it will be seen that the four radially ex-

tending air shafts 27, 28, 29 and 30 are connected at their rear end with a short length of an air conduit or tunnel 21 and reference being made to Figure 6 it will be seen that this air tunnel 21 has lateral connections of tubular formation, 48, 48a which communicate with the blower-air casings F' in which are located suction fans driven by engines G located at one side of the casings F'. Depending from the casings F' are the downwardly inclined air conduits 44 which open out from the bottom section of the envelope 10 and have terminals or outlet ends 45 exposed to the atmosphere and pointing towards the rear of the airship. This causes the outlet end 45 of the air conduit 44 to exhaust the air as the air blowers function. The slit 46 formed in the envelope allows for the conduit 44 to project thereout exteriorly of the airship. It is thus seen that instead of the air tunnel 21 running longitudinally and centrally of the airship from one end of the airship to the other end, that the relatively short length of the outlet air conduit 44 need only extend at the front section of the airship where it serves the same purpose of supplying the air shafts with the needed compressed air.

17 designates the interior construction of the main passenger cabin of the airship and 28 19 designates the landing gear of the machine. In the bulging or enlarged bodies 42 of the air shafts may be located motors 41 for driving the outside propellers 31 in order to assist in propelling the airship at an even 25 keel. The four connecting rods for operating the four shutters 33 are respectively designated 32, 32a, 32b and 32c. 40 designates the main control lever for effecting, if desired, the movement of the horizontal and vertical 40 rudders. 26 designates cross braces between units of reinforcing means. 47 designates the compartment or engine room for the air blowers and kindred parts. I do not limit myself to exact details of construction save 45 as appears in the appended claims.

What I desire to protect is:—

1. In an airship an air-suction stabilizer apparatus arranged therein and having radially disposed air shafts connected therewith and opening out of the nose end thereof to the atmosphere, an air supply tunnel disposed centrally in said airship, an air suction fan connected with said tunnel, and an intake conduit projecting out of the bottom 55 of the air ship and connected also to said suction fan.

2. In an airship, in combination a series of radially disposed air shafts opening out of the nose end thereof, propellers operatively carried in said air shafts and operating externally thereof, a common air tunnel for said air shafts, a vertically arranged air exhaust pipe having a lower terminal opening out of the envelope of the airship, and 60 a motor casing interposed between the air

tunnel and said exhaust pipe and connected to both.

3. In an airship a series of air shafts diverging outwardly and opening out of the nose end thereof, a common air supplying tunnel arranged at the front end of the airship and communicating with all of said air shafts, a motor casing connected to said air tunnel, and an air outlet pipe extending downwardly from said casing and opening 75 out of the bottom of said airship.

4. In an airship, in combination a longitudinal air tunnel, means transmitting compressed air thru said tunnel, a series of radially disposed air shafts opening out from 80 said tunnel into the nose end of the airship, shutters for regulating the passage of air thru said air shafts collectively and severally, means for controlling said shutters, an operator's room in the nose end of the airship, in which said controlling means are located, and windows in the airship in advance 85 of said operator's room commanding a view ahead of navigation conditions.

5. In an airship in combination a series 90 of separate air shafts opening out of the nose end of the ship, a shutter movably mounted in each of the air shafts, a platform below said air shafts, operator's room equipment on said platform, a window on the nose end of 95 the airship giving the operator a commanding view of navigation conditions ahead, and manually controlled mechanism on said platform designed to collectively and severally operate said shutters.

6. In an airship, a plurality of radially disposed air shafts opening out of the nose end thereof, a main air tunnel also opening out of the nose end of the airship being concentric with said air shafts and feeding air 105 thru the latter, a compressed-air power generating plant to which the main air tunnel is connected, a damper rotatably operated in each air shaft adjacent the free end thereof, pintles on said air shafts upon which the 110 dampers are mounted, cranks fixed upon said pintles externally of said air shafts, connecting rods for operating the several cranks selectively, a common shaft for all of said connecting rods having cranks connected to the latter, and manually controlled means for selectively operating said connecting rods.

7. In an airship, a central air tunnel opening out of the front end thereof four air shafts connected thereto and having terminals opening out of the front end of the airship, two of which are arranged at the dead centers and two at right angles thereto, propellers arranged externally of the airship and operating in the several air shafts, dampers in said air shafts, and manually operated selectively controlled mechanism for collectively or severally operating said shutters.

8. In an airship, an air tunnel extending 120 downwardly in the front portion thereof and 125

having a lower outlet exhaust terminal projecting out of and beneath the envelope of the airship and pointing to the rear of the ship, an air blower plant to which the upper terminal of said air tunnel is connected, and a plurality of radially separated independent but interconnected air shafts leading from said plant forwardly and divergingly and having their outer ends opening out of the airship.

9. In an airship stabilizing apparatus, an air suction plant located in the front end of the airship and consisting of a pair of spaced apart air blowers engines, an air tunnel having lateral offsets communicating with both of said blowers, a pair of downwardly extending air outlet conduits leading from said blowers and out thru the lower section of the airship to the atmosphere, and a plurality of collectively or independently controlled air shafts leading from said air tunnel to the extreme front end of the airship and opening out to the atmosphere.

In witness whereof he has hereunder set
25 his hand this 22nd day of October, 1929.

RALPH A. YELLI.
